Primary Examiner — Mimosa De(74) Attorney, Agent, or Firm — Philip H. Burrus, IVCLAIM

The ornamental design for a seating device, as shown and described.

DESCRIPTION

FIG. 1 is a front elevation view of a seating device showing our new design;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof; and,

FIG. 7 is a perspective view thereof.

All broken lines are included for the purpose of illustrating use and environment and form no part of the claimed design.

1 Claim, 4 Drawing Sheets(56)
